(57) **CLAIM**

(22) Filed: **Jan. 29, 2008**

The ornamental design for sunglasses without lenses but having six horizontal slats crossing the field of vision of each eye, as shown and described.

(51) **LOC (9) Cl.** **16-06**

DESCRIPTION

(52) **U.S. Cl.** **D16/301**

FIG. 1 is a perspective view of sunglasses without lenses but having six horizontal slats crossing the field of vision of each eye, illustrated with one temple piece in a collapsed position and another temple piece in an extended position, showing my new design;

(58) **Field of Classification Search** D16/101,

FIG. 2 is a front elevational view of the invention, illustrated with both temple pieces in the extended position;
